CLAIM

The ornamental design for an artificial novelty head, as shown and described.

DESCRIPTION

FIG. 1 is a front right perspective view of an artificial novelty head in accordance with my new design;

FIG. 2 is a front perspective view thereof;

FIG. 3 is a right-side perspective view thereof;

FIG. 4 is a rear perspective view thereof;

FIG. 5 is a left-side perspective view thereof;

FIG. 6 is a top perspective view thereof; and,

FIG. 7 is a bottom perspective view thereof.

The broken lines in the figures are for illustrative purposes only and form no part of the claimed design. The bottom surface portions shown entirely in broken lines form no part of the claimed design. The remainder of the broken lines, shown within the solid profiles and adjacent to the lines depicting the surface contour are included for the purpose of illustrating superficial details that form no part of the claimed design.
